UNITED STATES PATENT OFFICE.

JOSEPH BUREN EVANS, OF LOS ANGELES, CALIFORNIA.

METAL SEPARATOR.

Application filed December 13, 1924. Serial No. 755,781.

This invention is adapted to be employed for collecting metals out of metal-bearing sand, crushed ore and the like.

The device comprises a chute along which the material passes, and one object of the invention is to provide novel means for imparting movement to the chute, novel means being supplied for rotating, simultaneously, a plurality of agitators which operate in the chute.

It is within the province of the disclosure, to improve generally and to enhance the utility of devices of that sort to which the invention appertains, and other and further objects will be brought out as the description progresses.

Although a preferred form has been shown in the drawings, it will be understood that a mechanic, working within the scope of what is claimed, may make such changes as his skill may suggest, without departing from the spirit of the invention.

In the accompanying drawings:

Figure 1 shows, in side elevation, a device constructed in accordance with the invention; Figure 2 is a fragmental longitudinal section of the chute, the view showing the riffles and parts which cooperate therewith; Figure 3 is a rear elevation wherein parts are broken away; Figure 4 is a transverse section taken through the chute, parts being broken away; Figure 5 is a fragmental elevation showing a portion of the means whereby the chute is supported and mounted; Figure 6 is a section on the line 6-6 of Figure 5; Figure 7 is a sectional detail illustrating one of the adjustable bearings; Figure 8 is a section on the line 8-8 of Figure 7.

In carrying out the invention, there is provided a frame 1 which may be variously constructed without jeopardizing the utility of the invention. The frame 1 comprises standards 2 and 3 at each side of the machine, the standards being connected by a lower cross piece 4 and an upper cross piece 5. Slides 6 are mounted between the standards 2 and 3 for right line vertical adjustment, and are disposed at the upper ends of the standards, the slides 6 carrying bearings 7. As shown in Figure 7, the slides 6 are equipped in their lower edges with seats 29 wherein anti-friction members, such as balls 30, are mounted, the balls being engaged by adjusting devices, such as screws 31 threaded into the cross pieces 5, the lower ends of

the screws being slidably received in the cross pieces 4, the screws being equipped with turning heads 32 accessible between the cross pieces 4 and 5.

In the bearings 7, a shaft 8 is journaled, the shaft 8 carrying members 9 provided with peripheral projections 10. A shaft 11 is disposed at a much lower level than the shaft 8 and is journaled for rotation in bearings 12, located on the frame 1 near to the forward end thereof. The shaft 11 carries members 14, constructed like the members 9 on the shaft 8, and having projections 15.

A sprocket wheel 16 is secured to the shaft 11, a sprocket wheel 17 being mounted on the shaft 8. About the sprocket wheels 16 and 17 is engaged a chain 18. The shaft 8 is supplied with a pulley 19 about which passes a belt 20 engaged with a pulley 21 on a shaft 22 supported at 23 for rotation on the frame 1, the shaft 22 carrying a pulley 24 wherewith is engaged a driving belt 25.

Brackets 26 are mounted on the standards 3, each bracket carrying a substantially horizontal cushion 27. The brackets 26 are located near to the members 9, similar brackets 28 being mounted on the frame 1 slightly to the rear of the members 14 on the shaft 11.

The device comprises a downwardly and forwardly inclined chute 33 embodying a bottom 34, sides 35 and an upper end wall 36, the chute being open at its lower end. The chute carries upper supports 37, in the form of blocks, the said supports cooperating with the members 9 on the shaft 8. The chute is supplied with lower supports 38, in the form of blocks, coacting with the members 14 on the shaft 11.

At this point, it may be profitable to observe that, as indicated in Figure 3, the members 14 and 9 at one side of the chute 33 are so set with respect to the corresponding members at the other side of the chute, that, when the members 14 and 9 are rotated, the chute 33 will be rocked or oscillated transversely of an axis extended lengthwise of the chute. The members 14 and 9 may be alluded to as eccentrics cooperating with opposite side portions on the chute 33, the eccentrics at one side of the chute being so set with respect to the eccentrics at the other side of the chute that when all of the eccentrics are operated simultaneously, the chute will be rocked in a direction transverse to the path traversed by the

material as the material moves along the chute. The supports 37 are received between the upper portions of the brackets 26, and the lower supports 38 are similarly located with respect to the lower brackets 28. In view of the foregoing, the chute is prevented from having too much lateral side play. In order to prevent the chute 33 from moving downwardly, in the direction of its length, when the chute is in motion, it may be desirable to provide the upper supports 37 with outwardly projecting fingers 39, between which the upper portions of the brackets 26 are received.

15 The rear upper portion of the frame 1 carries a hopper 40 from which the material (either wet or dry) passes into the chute 33. Upwardly curved riffles 41 are secured at 42 to the bottom of the chute 33 and are spaced apart longitudinally of the chute. Inclined screens 43 extend above the riffles 41, in spaced relation thereto, the rear ends of the screens 43 being hinged at 45 to the bottom 34 of the chute 33, the screens being supported on cleats 44 carried by the sides 35 of the chute. Shafts 46 are journaled for rotation in the sides 35 of the chute 33 and are equipped with agitators 47 operating within the curved riffles 41.

20 There are beveled gears 48 on the shafts 46, the beveled gears 48 meshing with beveled pinions 49 on a shaft 50 extended longitudinally of the chute 33 and journaled in bearings 51 carried by one side of the chute. At its upper end, the shaft 50 is supplied with a beveled pinion 52 meshing with a beveled gear 65 on a transverse shaft 53 journaled in bearings 54 mounted on the upper end wall 36 of the chute 33. The 25 shaft 53 carries a pulley 55 cooperating with a belt 56 engaging a pulley 57 on the shaft 22. In order to take the slack out of the belt 56, a belt tightener is provided, and this belt tightener may be of any desired form. 30 As shown, the belt tightener embodies a shaft 58 journaled in bearings 59 on the frame 1, the shaft having a crank 60 whereon a heavy roller 61 is journaled, the roller 35 cooperating with one run of the belt 56, as clearly shown in Figure 1. In order that the shaft 58 may be under the control of an operator, the shaft is provided at one end with a handle 62.

35 In practical operation, the material from which the metal is to be removed is cast into the hopper 40, from whence the material moves downwardly through the chute 33. The material moves downwardly and forwardly, traversing the screens 43, the heavy metal, and some of the lighter material, of course, falling to the bottom 34 of the chute 33. The material, both heavy and light, is caught by the riffles 41 and, as the agitators 47 are rotated, the material 40 is stirred up, the heavier portions remain-

ing in the riffle, for the most part, and the lighter portions, along with a little of the heavy material, passing over the riffle 41 and upon the next screen 43, the process above described being repeated until, when 45 the material at length runs out of the lower end of the chute 33, the heavy metals will have been removed. The screens 43 may be turned up on their hinges 45 to permit the removal of the metal from the riffles 41. 50 Whilst the material is moving downwardly along the chute 33, the chute is being rocked transversely of its length, owing to the way in which the members 9 and 14, on the shafts 8 and 11, respectively, cooperate with the supports 37 and 38 on the chute.

55 The drives are as follows. The belt 25 and the pulley 24 rotate the shaft 22. From the shaft 22, motion is transmitted to the shaft 8, by the pulley 21, the belt 20 and the pulley 19. The shaft 8 operates the eccentric members 9. From the shaft 8, rotation is imparted to the shaft 11 and the eccentric members 14, by means of the sprocket wheel 17, the sprocket chain 18 and 60 the sprocket wheel 16.

65 Rotation is imparted to the agitators 47 by a train of elements embodying the belt 25, the pulley 24, the shaft 22, the pulley 57, the belt 56, the pulley 55, the shaft 53, the beveled gear 65, the beveled pinion 52, the shaft 50, the beveled pinions 49, and the beveled pinions 48 on the shafts 47. Referring to Figure 1, it will be observed that one run of the belt 56 is bulged inwardly by the action of the belt tightener 61—60. When the chute 33 is rocked in a direction transverse to its length, by the action of the members 9 and 14, the crank 60 of the shaft 58 will teeter up and down a little thereby permitting the belt 56 to have slack enough so that the aforesaid transverse rocking movement of the chute 33 may take place without stopping the rotation of the shaft 50 and the agitators 47. If at any time during the operation of the device, the operator wishes to stop the rotation of the agitators 47, this can be done by swinging the roller 61 out of engagement with the belt 56, by way of the handle 62, the belt 56 then being so slack that it will not impart rotation to the shaft 53 by way of the pulley 55.

70 If the vertical movement of the chute 33 is considerable, as the chute rocks from side to side, the cushions 27 will prevent the chute from bumping too hard on the brackets 26. In order to vary the pitch of the chute 33 with respect to the horizontal parts 9—8—7—6 may be raised or lowered through the instrumentality of the screws 125 31.

75 Having thus described the invention, what is claimed is:

80 1. In a device of the class described, a chute, means for mounting the chute for 130

movement, riffles in the chute, agitators journaled in the chute and cooperating with the riffles, means for imparting movement to the chute, means for operating the agitators, and screens in the chute and inclined from the bottom of the chute, the screens having free ends extending above the riffles and the agitators.

2. In a device of the class described, a chute, pairs of members whereon the chute rests, the pairs being spaced apart longitudinally on the chute, the members of each pair being spaced apart transversely of the chute, each member comprising a plurality of projections adapted to cooperate with the chute, the projections of the members of each pair being disposed out of registration transversely of the chute, the relative positions of the projections and the progression of a plurality of projections giving the chute a transverse rocking movement and a plurality of bumping movements each time that each member is rotated, and means

for rotating said members in the relation specified with respect to each other. 25

3. In a device of the class described, an elongated chute, means for mounting the chute for rocking movement in a direction transverse to its length, a riffle in the chute and disposed transversely of the chute and approximately parallel to the direction in which the chute rocks, an agitator journaled in the chute and cooperating with the riffle, the agitator being disposed approximately parallel to the riffle, mechanism connected to 35 the agitator for rotating the agitator, mechanism for rocking the chute in a direction transverse to its length, and means for driving both of said mechanisms from a single point of force application located on 40 the said device.

In testimony that I claim the foregoing as my own, I have hereto affixed my signature.

JOSEPH BUREN EVANS.
